REFRIGERATING APPARATUS

Filed Dec. 13, 1926

UNITED STATES PATENT OFFICE

HARRY B. HULL, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed December 13, 1926. Serial No. 154,329.

This invention relates to refrigerating systems and apparatus.

One of the objects of the invention is to provide improved refrigerating apparatus suitable for small plants such as household or store cabinets.

Another object is to provide a refrigerating system in which a plurality of refrigerating devices are arranged to operate alternately.

Another object is to provide apparatus in which the refrigerating phase of the cycle is materially prolonged without a proportionate increase in operating expense.

Another object is to utilize the waste heat of a compression system to produce refrigeration.

Another object is to combine a compression and an absorption system.

Still other objects will appear in the following description and claims.

The attached drawings show one form which the invention may take.

In the drawings:

Fig. 1 is a diagrammatic elevation of apparatus embodying the invention, and

Fig. 2 is a section on the line 2—2 of Fig. 1.

Refrigerating devices heretofore applied to cooling cabinets have been either of the compression or absorption type. Each type has its own inherent advantages and disadvantages when applied to particular situations.

The absorption systems usually constructed for service of this character refrigerate in-35 termittently, and a considerable interval necessarily occurs between refrigerating phases of its cycle during which heat must be applied to the system. Hence such a system is not adapted to service requiring refrigerating continuously or even the greater portion 40 of the cycle.

Compression systems are adapted to furnish either continuous or intermittent refrigeration. However, while they are refrigerating, certain portions of the system must be cooled and the heat taken therefrom must be dissipated outside the system. This heat is lost energy.

My invention contemplates the combining 50 of two refrigeration systems, one of which

may be of the compression type, to prolong the refrigerating period of the apparatus. It also contemplates utilizing the otherwise waste heat of a compression system to effect refrigeration.

One manner of carrying out my invention is as follows: I provide a compartment 10 to be cooled, having a top wall 11 upon which may be mounted a compressor 12 and motor 13 for driving the latter. The compressor 55 pumps gaseous refrigerant, such as sulfur dioxide, through a coil of tubing 14, and if desired through an additional coil 15, in one or both of which the refrigerant is condensed to liquid form, after which it flows through an expansion valve 16^a to an evaporator 16. The evaporation of the refrigerant cools the cabinet in the well known manner, the refrigerant being withdrawn by the compressor 60 through suction pipe 17, compressed 65 again, and circulated through the system.

Hot gaseous refrigerant coming from the compressor must be cooled in order to condense. Heretofore this has been accomplished by circulating air or water over the condenser and dissipating outside the cabinet the heat thus absorbed. This heat is wasted energy.

I provide means for converting at least a part of this heat into useful work in the form of refrigeration. Around the condenser 14, I 75 construct a generator-absorber 20, which is filled with any suitable absorbent material 21, preferably a dry solid absorbent, an example of which is calcium chloride. A conduit 22 leads from the generator-absorber to a condenser 23 from the other end of which a conduit 24 leads to an evaporator 25 which may be placed wherever cooling is desired, preferably in the cooling compartment 10. The generator absorber, condenser 23 and 80 evaporator 25 constitute an absorption system which may contain any suitable refrigerant such as anhydrous ammonia.

Preferably the coils 15 and 23 are mounted near the motor and a fan 30 is mounted on 85 the motor shaft for cooling them.

The generator-absorber may be allowed to cool naturally, or if desired, any suitable means may be provided for cooling it when the compressor is not operating, such as cir- 100

culating water controlled by an automatic valve, or as shown in the drawings, a fan 31 driven by a motor 32.

A temperature responsive device 33 may be placed in the compartment 10 for operating a controlling switch 34 in response to the refrigerating demands of the compartment. When the switch is in the full line position shown, it closes a circuit to actuate motor 13 to drive the compressor. When the switch is in dotted line position, the circuit of motor 13 is open, but the circuit to motor 32 or other cooling apparatus is closed.

Operation

Assuming the compartment 10 is warm, the ammonia in the absorption system is held in the absorbent 21, and liquid sulfur dioxide is in the evaporator 16. Switch 34 is in full line position and motor 13 is operating the compressor. The compressor reduces the pressure in the evaporator permitting the sulfur dioxide to evaporate and absorb heat from the compartment. Hot compressed gaseous sulfur dioxide passes into the coil 14 heating the generator-absorber and cooling the sulfur dioxide. The latter passes into the coil 15 where it is further cooled by the fan 30. When the sulfur dioxide leaves the coil 15 it is liquid, and flows into evaporator 16, where it is again evaporated to absorb heat as before.

The hot sulfur dioxide gas heats the absorbent 14 to drive off ammonia. The latter passes into coil 23 where it is cooled by fan 30 and condensed, flowing into evaporator 25.

The compressor continues operating until the temperature of the compartment reaches a predetermined low point, when the thermostat 33 moves the switch 34 to dotted line position. The compressor and fan 30 now stop, and motor 32 and fan 31 operate to cool the generator-absorber. Cooling of the latter causes the absorbent to take up ammonia, inducing evaporation in the evaporator 25 which further cools the compartment 10. After the absorbent has taken up all the ammonia it can, refrigeration ceases, and the compartment 10 will begin to get warm. When a predetermined high temperature has been reached, the thermostat 33 will again move the switch 34 to start the motor 13. The cycle will thus repeat itself indefinitely.

It will be seen that the absorption system refrigerates during the intervals between the refrigerating phases of the cycle of the compression system. This prolongs the refrigerating period at a slight operating cost, since the motor 32 or other cooling control requires but little power in comparison with the motor 13.

While the form of embodiment of the present invention as herein disclosed, constitutes a preferred form, it is to be understood that other forms might be adopted, all coming

within the scope of the claims which follow.

What is claimed is as follows:

1. In refrigerating apparatus, in combination, a compression refrigerating system including a device to be cooled, and an absorption refrigerating system including a generator, the generator being arranged to absorb heat from said device. 70

2. In refrigerating apparatus, in combination, a compression refrigeration system including a condenser and an absorption refrigerating system including a generator, the generator and condenser being in heat exchange relation. 75

3. In refrigerating apparatus, in combination, a compressor adapted to be operated intermittently, a condenser, an absorber-generator for cooling the condenser, and means for cooling the absorber-generator when the compressor is not operating. 80

4. In refrigerating apparatus, in combination, a compressor, a condenser, an absorber-generator for cooling the condenser, means for cooling the absorber-generator and control means operated automatically in response to the refrigerating demand of the system, said control means being adapted when in one position to permit operation of the compressor alone, and in another position to permit the operation of the means for cooling the absorber-generator alone. 85

5. Refrigerating apparatus comprising in combination a compartment to be cooled, a pair of refrigerating devices for cooling the compartment, control means moved to either of two positions in response to the refrigerating demand of the compartment, the control means being arranged to effect operation of one refrigerating device when in one position and the other refrigerating device when in the other position. 100

6. In a refrigerating apparatus, in combination, a compression refrigerating system including a device to be cooled, and an absorption refrigerating system arranged to abstract heat from the device. 110

7. In a refrigerating apparatus, in combination, a compression refrigerating system including a condenser to be cooled, and an absorption refrigerating system arranged to abstract heat from the condenser. 115

8. In refrigerating apparatus, in combination, a compression refrigerating system including a device to be cooled, and an absorption refrigerating system including a device to be heated, said devices being arranged in heat exchange relation. 120

In testimony whereof I hereto affix my signature.

HARRY B. HULL. 125
